UNITED STATES PATENT OFFICE.

OTTO NELSON, OF CHICAGO, ILLINOIS, ASSIGNOR OF ONE-FOURTH TO DANIEL P. TETER
AND ONE-FOURTH TO PETER LIGNELL, BOTH OF CHICAGO, ILLINOIS.

GAS ENGINE.

Application filed March 16, 1921. Serial No. 452,677.

To all whom it may concern:

Be it known that I, OTTO NELSON, a citizen of the United States, residing at Chicago, in the county of Cook and State of Illinois, have invented certain new and useful Improvements in Gas Engines, of which the following is a specification.

My invention relates to gas engines and has for one of its objects the provision of a simple and efficient timing means for gas engines.

A further object is the provision of means for drawing a full charge to a point adjacent the working cylinder by means outside 15 of said cylinder.

A still further object is the provision of a simple and efficient means for opening and closing the ports of a gas engine in definite relations with each other.

20 Other objects will appear hereinafter.

An embodiment of my invention is illustrated in the accompanying drawings, forming a part of this specification, and in which—

25 Fig. 1 is a vertical section taken through an engine embodying my invention;

Fig. 2 is a section taken on line 2—2 of Fig. 1; and

30 Fig. 3 is a fragmental section taken as looking from line 3—3 in Fig. 2.

Referring more particularly to the drawings, I have indicated a working cylinder 5 mounted on a crank casing 6 and having a working piston 7 mounted in said cylinder. 35 Mounted in the crank case is a crank shaft 8 and the crank shaft is connected to the piston 7 by a connecting link 9. These parts may be of ordinary construction. The upper part of the cylinder 5 may be

40 provided with a water jacket 10 in the usual manner for radiating heat from said cylinder in use. At the top of the cylinder 5 I have indicated a spark plug 11 which is adapted to function in the ordinary manner.

45 At one side of the cylinder 5 I have indicated an intake valve cylinder 12 and an exhaust valve cylinder 13. These cylinders may be provided with a water jacket which may be a continuation of water jacket 10, or 50 cooled in any other desirable manner. The cylinders 12 and 13 may be formed with removable tubes 14 which provides their inner surface or bores when so desired, or the tubes 14 may be dispensed with and their

inner walls formed in any desirable manner. 55 The provision of the tubes 14 provides a simple and easy manner for making the ports. The port 15 which communicates between the cylinder 5 and cylinders 12 and 13 preferably extends entirely around the tubes 14, as clearly indicated in Fig. 2, and said tubes are each provided with a plurality of ports 16 which are arranged entirely around said tubes. This provides means whereby the fluid passing from intake cylinder 12 60 65 into cylinder 5 may pass out through the ports 16 entirely around its tube 14 and the fluid passing from cylinder 5 into cylinder 13 can pass through all of the ports 16 into its tube 14. I prefer to have the combined 70 areas of openings 16 in each of the tubes 14 substantially equal or slightly greater than the cross area of said tube. This relation, however, may be changed in accordance with any desired construction. The arrangement 75 of the ports 16 entirely around the tubes 14 also facilitates cooling the adjacent parts of the cylinder walls.

Slidably mounted in cylinders 12 and 13 are plungers 17 and 18. The plungers 17 80 and 18 and piston 7 are each provided with the usual packing rings 19. A connecting rod 20 connects each of plungers 17 and 18 with a crank or cam shaft 21, and the latter is connected by gears 22 and 23 with crank 85 shaft 8 in a relation so that the crank shaft 8 makes two revolutions to one revolution of the crank shaft 21. The plungers 17 and 18, connecting rods 20, and the cranks of crank shaft 21 are arranged so as to properly time 90 the engine. I preferably arrange the cranks on crank shaft 21 at substantially 90 degrees apart. The axis 24 of the connection between plunger 17 and its connecting rod 20 is substantially directly over the axis of 95 crank shaft 21 so that the intake port of the engine may be arranged to remain open during the downward movement or suction stroke of the piston 7. The axis 25 of the connection between plunger 18 and its connecting rod 20 is preferably arranged to one side of a vertical line passing through the axis of shaft 21 so that the exhaust port of the engine will be opened a longer time than the intake port and near the end of the 100 working stroke of piston 7. The distance between parallel lines passing through points 24 and 25 will vary according to the 105

speed it is desired the engine to run, the farther apart these lines are, the faster the time of the engine will be.

In the arrangement of the parts as herein shown, the plunger 18 is in a position where it begins to uncover openings 16 in the sleeve 14 of the exhaust valve cylinder in Fig. 1. It will be noted that the piston 7 is not quite to the end of its working stroke, as indicated by the position of crank shaft 8 and a direction indicating arrow 26. The arrangement is such that during the continued movement of crank shaft 8 around through its bottom dead center, and to its top dead center the crank shaft 21 will move from the position shown to a point 27 when the plunger 18 will be brought back to the position shown in Fig. 1. This will permit the exhaust valve to be opened somewhat more than one stroke of piston 7. The length of plunger 17 and its particular relation to the crank shaft 21 will cause it to begin opening the intake port when its crank reaches a point 28 and then the intake port will remain open while its crank is passing from point 28 to point 27, and during this movement the crank 8 will be moved from its upper dead center to its lower dead center.

With the arrangement just set forth it will be apparent that the intake plunger 17 will move from its position indicated in Fig. 1 down to a position where it begins to uncover ports 16 before the piston 7 begins to draw fuel into the cylinder 5. This provides drawing fuel from the carburetor to a position very close to the port 15 ready to be taken up by the suction of piston 7 in cylinder 5 as soon as the intake port is open. This construction then provides means for bringing a charge of fuel to the cylinder ready to be taken up by the latter as soon as the intake port is open. The conical top portions of the plungers 17 and 18 will help to direct the fuel into the intake ports and

to direct the discharge gases from the exhaust ports to the center of the cylinder 13 and then up out through exhaust pipe 29.

I claim:

1. In an engine of the character described having a piston, a crank shaft operatively connected with said piston, an intake cylinder and an exhaust cylinder connected with the working cylinder of said engine, plunger valves operatively disposed in said intake and exhaust cylinders, an auxiliary crank shaft operatively connected with said first named crank shaft, a connecting rod connecting said auxiliary crank shaft with said plunger in said intake cylinder at a point adjacent the periphery of said plunger and in vertical alinement with the axis of said auxiliary crank shaft, and a connecting rod connecting said auxiliary crank shaft with the plunger and said exhaust cylinder at a point adjacent the periphery of said plunger and out of alinement with the axis of said auxiliary crank shaft.

2. In an engine of the character described having an exhaust cylinder and an intake cylinder, a plunger for said intake cylinder, a plunger for said exhaust cylinder, a crank shaft, a connecting rod connected to said intake plunger at a point adjacent the periphery thereof, and a connecting rod connected with said exhaust plunger at a point adjacent the periphery thereof, said connecting rods each having its lower end connected with said crank shaft, whereby the connecting rod for said intake cylinder joins said intake plunger at a point above the axis of said crank, and the connecting rod for said exhaust cylinder joins said exhaust plunger at a point out of alinement with said crank shaft.

In testimony whereof I have signed my name to this specification on this 14th day of March, A. D. 1921.

OTTO NELSON.
